A. L. ARENBERG,

VEHICLE LAMP,

APPLICATION FILED JAN. 8, 1920.

1,347,886.

Patented July 27, 1920.

INVENTOR:
ALBERT L. ARENBERG,

BY Cheever & Cox

ATKINS.

UNITED STATES PATENT OFFICE.

ALBERT L. ARENBERG, OF CHICAGO, ILLINOIS.

VEHICLE-LAMP.

1,347,886.

Specification of Letters Patent. Patented July 27, 1920.

Application filed January 8, 1920. Serial No. 350,072.

To all whom it may concern:

Be it known that I, ALBERT L. ARENBERG, a citizen of the United States, residing at Chicago, in the county of Cook and State of Illinois, have invented a certain new and useful Improvement in Vehicle-Lamps, of which the following is a specification.

My invention relates to vehicle lamps and is especially applicable to that type of lamp commonly supported within reach of the driver and movably mounted in such manner that the beam of light can be sent in various directions to illuminate particular parts of the roadway. Lamps of this character are frequently called "search lights" and "spot lights." These lamps are commonly mounted just outside of the vehicle body or top and consequently are not hidden either from the front or rear. The underlying object of my invention is to provide a lamp of this character which may be used to throw a powerful beam of light forward in driving and both forward and backward when the vehicle is standing still or "parked." In the best form, the rearward beam has a red lens within its path, thus showing a red light at the rear. By preference, this red lens is a condensing lens, and by its use the rays will be confined within the desired angle, to warn drivers approaching from the rear.

I accomplish my objects by the mechanism illustrated in the accompanying drawings in which,

35 Figure 1 is a side sectional elevation of the assembled device, and

Fig. 2 is a front elevation showing part of the front glass broken away to reveal the parts behind it.

40 Like numerals denote like parts throughout the several views.

In the particular form selected to illustrate the invention, the main lamp bulb 1 is adapted to be inserted into a socket or receptacle 2 which, by preference, is located at the axis of a parabolic or other reflector 3. According to the best practice, the front of the reflector is closed by a plate of glass 5. A bezel 6 holds the reflector and glass 50 to the body or housing 7 of the lamp. The lamp body may, of course, assume various shapes and designs and may be supported in various ways. As spot lights and search lights for vehicles are well known, a description of the means for supporting the lamp body is unnecessary.

An auxiliary lamp bulb 10 is adapted to be supported in a socket or receptacle 12 mounted upon the bottom of the lamp body. The bulb and receptacle are so positioned and proportioned that the bulb comes within an opening 14 formed in the reflector. This opening is located preferably about half way between the bottom and the center of the reflector. In any event, the construction is such that when the auxiliary bulb 10 is in place and lighted, it will cast rays both forward from the reflector and rearward through an opening 15 in the lamp body. In the best form, a lens 16 is mounted in the opening 15 and, if the lens is of the condensing type, the rearward rays are concentrated and directed straight backward where they may be seen by vehicles approaching from behind. By preference, the lens 16 is red after the manner of a tail light.

While not essential, it is desirable to mount a mirror 20 on the back of the lamp body to enable the driver to see what is behind him when driving.

Operation: The main bulb 1 and auxiliary bulb 10 are adapted to be turned on and off independently of each other. Means whereby this may be accomplished are so well known as to render detailed description unnecessary. When the vehicle is being driven at night, the driver turns on the main bulb 1 with the result that a powerful beam of light is sent forward and a flood of light is thrown on any desired portion of the road. The auxiliary lamp is left unlighted, ordinarily, the reason being that moving vehicles are commonly required to have independent tail lights for night driving. When the driver has reached his destination and wishes to leave the vehicle at the curb or to park it, he turns out the light from the main bulb and turns on the light in the auxiliary bulb. When this is done, the light from the auxiliary bulb is thrown partly forward and partly backward, the forward rays either passing directly through the glass front 5 or impinging upon the front surface of the reflector and being cast in a forward direction. This gives an abundant amount of light at the front of the lamp for parking purposes and serves as abundant warning to any driver approaching from the front. The rays passing rearward pass through the lens 16, thus creating a rearward projecting beam of light which, as above stated, is pref-

erably colored red and condensed by the lens so as to form abundant warning to a driver approaching from the rear.

The sizes of the two bulbs may, of course, be varied to suit the desires of the vehicle owner, but I have found that a two or three candle power lamp is ordinarily quite sufficient for the auxiliary light. When the auxiliary light is on, it is unnecessary to 10 keep the tail light and the front lamps of the vehicle illuminated, for a lamp embodying this invention, is higher from the ground and out nearer the center of the road, especially when the device is mounted on the 15 left side of the vehicle as is the most common practice today. It will thus be observed that my device combines within itself the characteristics of a headlight or search light when driving and a combined head- 20 light and tail light when parking. It promotes economy for it enables a single small power lamp to furnish the illumination for both head light and tail light while parking. This latter characteristic produces a big saving 25 in actual power drawn from the storage batteries and thus lengthens their life. This

will be greatly appreciated by drivers who realize the calls made upon the battery of an ordinary motor vehicle.

Having thus described my invention what 30 I claim as new and desire to secure by Letters Patent, is:

A vehicle lamp having a casing provided with a substantially parabolic reflector adapted to throw the light rays forward, 35 the reflector having means for supporting the main lamp bulb approximately at the axis of the reflector with the filament approximately at the focus of the reflector, the reflector also having an opening noncen- 40 trally located, an auxiliary lamp placed in juxtaposition to said opening whereby the rays may be projected both forward and backward, the casing also having an opening in the back, and a transparent body extending 45 across the opening in the casing substantially directly back of the auxiliary lamp.

In witness whereof, I have hereunto subscribed my name.

ALBERT L. ARENBERG.
